[57] CLAIM

The ornamental design for an escutcheon for a whirlpool jet nozzle, as shown and described.

DESCRIPTION

FIG. 1 is a front elevational view of an escutcheon for a whirlpool jet nozzle showing my new design;

FIG. 2 is a right side elevational view thereof, the left side being a mirror image of the right side;

FIG. 3 is a bottom plan view thereof, the top being a mirror image of the bottom;

FIG. 4 is a rear elevational view thereof; and,

FIG. 5 is a rear perspective view thereof.

FIG. 1

FIG. 2

FIG. 3

FIG. 4

FIG. 5
